UNITED STATES PATENT OFFICE.

LINUS G. READ, OF BRIDGEPORT, CONNECTICUT.

GOLF-CLUB-GRIPPING DEVICE.

Application filed August 10, 1922, Serial No. 580,904. Renewed November 28, 1923.

To all whom it may concern:

Be it known that LINUS G. READ, a citizen of the United States, and resident of Bridgeport, in the county of Fairfield and State of Connecticut, has invented certain new and useful Improvements in Golf-Club-Gripping Devices, of which the following is a specification.

My invention relates to an improved form 10 of golf club gripping device for use upon the index finger and thumb of either the right or left or both hands of a golf player to enable him to grip a golf club more advantageously than with the bare hands.

15 The game of golf is obviously a scientific game, the more essential feat of which is to properly drive and control the ball. This means that the ball must be struck with great care, so the direction of flight will be accurate and so that the distance which the ball travels is reasonably great.

From the drawings it will be noted that, briefly speaking, the device includes a separate finger and thumb covering which are 25 connected together by a strap, the end portions of which are attached to the two said covering members.

I find that the portion of the human hand between the index finger and thumb of the 30 average amateur player does not fill in closely around a golf stick and thus forms a pocket; therefore such a player meets with difficulty in gripping a club and swinging it to the best advantage and so that the required force may be imparted to the ball 35 and it controlled as desired, the control of the ball being the essential requisite to success.

With these and other objects in view the 40 invention resides and consists in the construction and novel combination and arrangement of parts hereinafter more fully described, illustrated in the accompanying drawings, and pointed out in the claims 45 hereto appended, it being understood that various changes in the form, proportion, size and minor details of construction within the scope of the claims may be resorted to without departure from the spirit or sacrificing any of the advantages of the invention.

Similar characters of reference denote like or corresponding parts through the several figures of the accompanying drawings form-

ing a part of this specification, and upon 55 which,

Fig. 1 shows an elevational view of a hand upon the forefinger and thumb of which one of my improved golf club gripping devices is shown applied in the act of 60 gripping a golf club.

Fig. 2 is a further elevational view of a human hand upon the thumb and forefinger of which my improved gripping device is shown in a slightly different position 65 from that shown in Fig. 1; and

Fig. 3 shows a detached view of the invention.

Referring in detail to the characters of reference marked upon the drawing, it will be 70 seen that the finger covering A comprises a sheath and the thumb covering B is somewhat similarly made to also form a sheath. These sheaths may be formed of leather, canvas or other suitable material as will be noted 75 and each are cut, assembled and stitched to include a single stitched seam a thus forming a covering of proper size and proportion that may readily be slipped on the finger in one instance and thumb in the other, 80 similar to that of a leather glove.

These two sheaths are connected together by a strip C, one end portion d of which may be secured as by stitching to the finger member A and the other end portion e of which preferably encircles and is secured to the thumb piece B. In this respect it will further be noted that one end of the strap C is attached at a point slightly beyond the second joint of the forefinger and the other end is secured outside of the first joint of the thumb, and obviously form a bridge which when the forefinger and thumb are gripping a club, better serves to support the club and prevent it from turning in the hand. It will be further noted that the end d of this strap attached to the finger sheath is disposed substantially lengthwise thereon while the other end portion e is secured crosswise and extended around the thumb sheath B. It will thus be seen that when the two sheaths are positioned on the hand and the hand is in the act of gripping a golf club the face of the strap will be disposed flat against and around the side of the shaft of the club in a manner to bridge across and firmly support the same in the upper part 105 of the hand.

- In practice this cross strap or bridge from the forefinger to the thumb establishes a definite and well supported axis of motion in the swinging of the club, acting as it were as a pivotal point, consequently the club can be swung with a greater feeling of confidence as well as increased degree of accuracy, thereby adding very materially to the proficiency of the player.
- 10 It will further be apparent that the bridge applied in this manner supports the club away from the inner upper portions of the hand so that the same will not become distorted, sore or calloused as is usual and objectionable with the majority of players.

Having thus described my invention, what I claim and desire to secure by Letters Patent is:—

1. A golf club gripping device comprising 20 a pair of finger sheaths, a golf club embracing and positioning strap, one flat end portion of which is secured against one sheath and the other end portion secured flat against the other sheath in a manner to 25 connect the adjacent faces of the finger sheaths together, and to embrace the club intermediately the ends of said other sheath and with the club in parallel relation to said other sheath.
- 30 2. A golf club gripping device comprising a finger sheath and a thumb sheath, a strap connecting the two, one end portion of the said strap being connected to the gripping face of one end portion of one of said sheaths

and the other connected to the inner face 35 of the other sheath in a manner to also form a reinforced wearing portion.

3. A golf club gripping device comprising a pair of finger sheaths and a connecting strap, one end of which is disposed and secured to and lengthwise of the finger sheath and the other end secured crosswise of the thumb sheath.

4. In a golf club gripping device of the class described the combination with a finger 45 sheath and a thumb sheath, of a strap, the end portions of which are respectively connected to each and in a manner so that its flat side will engage and encircle the surface of a golf stick when gripped.

5. A golf club gripping device comprising a finger sheath and a thumb sheath, a strap connecting the two, one end portion of the said strap being attached to the finger sheath at a point substantially coinciding with the 55 position of the second joint of the finger and the other end of said strap being connected to the thumb sheath at a point substantially coinciding with the position of the first joint of the thumb.

Signed at Bridgeport, in the county of Fairfield and State of Connecticut, this 8th day of August, A. D. 1922.
